(57) **CLAIM**

The ornamental design for a table lamp, as shown and described.

DESCRIPTION

FIG. 1 is a front elevational view of a table lamp showing my new design;

FIG. 2 is a side elevational view thereof, the side opposite being a mirror image of that shown;

FIG. 3 is a top plan view thereof;

FIG. 4 is a bottom plan view thereof;

FIG. 5 is an enlarged fragmentary front elevational view thereof, with the remaining portions of the table lamp omitted for clarity of illustration; and,

FIG. 6 is an enlarged fragmentary perspective view of the base thereof, with the remaining portions of the table lamp omitted for clarity of illustration.
